UNITED STATES PATENT OFFICE.

WILLIAM JOHN SCHLACKS, OF CHICAGO, ILLINOIS, ASSIGNOR TO McCORD AND COMPANY, OF CHICAGO, ILLINOIS, A CORPORATION OF NEW JERSEY.

FORCE-FEED LUBRICATOR.

1,145,515.

Specification of Letters Patent.

Patented July 6, 1915.

Application filed August 7, 1913. Serial No. 783,580.

To all whom it may concern:

Be it known that I, WILLIAM J. SCHLACKS, a citizen of the United States, residing at Chicago, in the county of Cook and State of Illinois, have invented certain new and useful Improvements in Force-Feed Lubricators; and I do hereby declare the following to be a full, clear, and exact description of the invention, such as will enable others skilled in the art to which it appertains to make and use the same.

My present invention relates to force feed lubricating and is more particularly directed to the improvement of force feed locomotive lubricators of the type wherein reciprocating pumps are employed to deliver the oil under pressure to the valves, cylinders, or other parts to be lubricated.

In systems of force feed lubrication for valves, journals and cylinders of locomotives, for example, it has hitherto been customary to use one pump for each valve, steam channel or other part to receive the lubricant, under which arrangement the oil would be positively fed or delivered during approximately one-half of the time only, to-wit, while the pump was making its working stroke. With such an arrangement, it has been found impossible to reduce the oil consumption to the minimum of oil required for the proper lubrication, for the reason that in reducing the number of strokes of the pump per number of revolutions of the driving wheels of a locomotive, there resulted an interim of dry bearing, due to the long time consumed in the suction or return stroke of the pump plunger. It occurred to me that the most economical use of oil in these lubricators could only be accomplished by providing pump mechanism which would deliver the oil to a particular bearing or point of delivery, by an approximately continuous action and under approximately constant pressure. I produced this ideal operation by connecting two pumps to one pipe line or oil delivery conduit, and by arranging these two pumps to operate alternately, so that the one pump would draw oil into its chamber while the other pump was forcing it to the bearing, or point of delivery. Of course, more than two pumps might be connected to one pipe line, or a double acting pump, to-wit, a pump arranged to positively force oil under both movements of the pump plunger, could also accomplish

this continuously acting force feed under approximately constant pressure.

This arrangement permits the reduction by one-half, the number of revolutions of the pump actuating shaft and, in fact, I have found, in the use of this improved pump, that we can reduce the oil consumption materially, and can reduce more than one-half, the speed that the pump actuating shaft was necessarily run at with single acting pumps. The continuous delivery of oil under approximately constant pressure permits the oil consumption to be reduced to a minimum, which will not cause waste, and which prevents intervals of dry bearing.

In the accompanying drawings, which illustrate the invention, like characters indicate like parts throughout the several views.

Referring to the drawings, Figure 1 is a plan view, showing a locomotive lubricator pump mechanism, embodying my invention; Fig. 2 is a side elevation of the pump mechanism, shown in Fig. 1, some parts being broken away; and Fig. 3 is a transverse vertical section, taken approximately on the line xx'xx' on Fig. 2.

The numeral 1 indicates a casing affording a suitable oil well and which well is kept supplied with oil from any suitable source.

The numeral 2 indicates a pump actuating shaft extended through the oil well and mounted in suitable bearings on the oil well casing 1. This shaft is adapted to be rotated in any suitable way and, when applied to a locomotive, the connections for driving the same will, as is customary, be arranged to drive the said shaft at a speed proportioned to the speed of rotation of the engine drive wheels. Inside of the oil well casing, the shaft 2 is provided with pump actuating eccentrics 3. As shown, there are two of these eccentrics, and they are set one-hundred eighty degrees apart. The eccentrics 3 work in elliptical eccentric straps 4 carried by reciprocating shafts 5 that are mounted for vertical sliding movements in suitable bearings in the top and bottom of the casing 1.

At their upper ends, the reciprocating shafts 5 carry cross heads 6, each of which is connected to the upper end of a pair of pump plungers 7. These pump plungers 7 work through stuffing boxes 8 and into plunger seats 9 of pump casings 10, which

latter are shown as rigidly secured on the top of the oil well casing 1. The lower extremities of the pump plunger seats 9 are, as shown, connected to the upper ends of pipes 11, the lower ends of which terminate near the bottom of the oil well and are preferably provided with strainers 12. Just above the upper ends of the pipes 11, the plunger seats 9 are equipped with gravity seated check valves 13. Above the valves 13, the plunger seats 9 are connected to oil discharge ducts 14, formed in the pump casings 10 and terminating in threaded coupling heads 15. In the oil ducts 14 are gravity seated check valves 16. The valves 13 and 16 coöperate with the pump plungers 7 in the customary way to produce a pumping action when the said pump plungers are reciprocated. As is obvious, the check valves 13 will open to permit the pump plungers to draw oil upward, and will check a reverse flow, while the valves 16 open to permit the oil to be discharged or forced onward by the pump.

For the purposes of the following illustrations, pumps from left toward the right, Figs. 1 and 2, will be referred to as pumps Nos. 1, 2, 3 and 4. It is evident that the plungers of the pumps 1 and 2 will be given downward or working strokes, while the plungers of the pumps 3 and 4 are being given upward or return movements, and vice versa, this being due to the arrangement of the eccentric 8 and the described connections of the pump plungers thereto.

In carrying out my invention in connection with a pump of the type, above described, pumps 1 and 3 are connected for a

common discharge, and pumps 2 and 4 are likewise connected for common discharge. This, as shown, is accomplished by providing oil delivery pipes 17 and 18, the former of which has branches 17^a connected to the coupling heads 15 of pumps 1 and 3, and the latter of which has branches 18^a connected to the coupling heads 15 of pumps 2 and 4. Of course, the said oil delivery pipes 17 and 18 may have branches for delivering each to a multiplicity of bearings, cylinders, steam passages, or the like.

What I claim is:—

1. In a force feed lubricating system, a plurality of pumps having plungers connected in sets, the discharge conduits of the pumps of one set being connected with discharge conduits of the pumps of the other set, combined with means for simultaneously moving the pump plungers of the one set in opposite directions, substantially as and for the purposes set forth.

2. In a force feed lubricating system, a plurality of pumps having plungers connected in sets, the discharge conduits of the pumps of the one set being connected with discharge conduits of pumps of another set, combined with means for operating the said sets of connected plungers in succession, whereby said pumps conjointly deliver oil continuously to several points of delivery under approximately constant pressure.

In testimony whereof I affix my signature in presence of two witnesses.

WILLIAM JOHN SCHLACKS.
